UNITED STATES PATENT OFFICE.

CHARLES EDWARD SANTO, OF LONDON, ONTARIO, CANADA.

SPRING-HINGE.

1,107,708.

Specification of Letters Patent. Patented Aug. 18, 1914.

Application filed February 20, 1914. Serial No. 820,013.

To all whom it may concern:

Be it known that I, CHARLES EDWARD SANTO, of London, Province of Ontario, Dominion of Canada, have invented certain new and useful Improvements in Spring-Hinges, of which the following is a specification.

This invention relates to spring hinges of the type including a checking device, and the objects of the invention are to reduce the number of working parts, to render the device less conspicuous, to enable it to be wholly located in a small recess in the door, and generally to simplify and improve the construction of the working parts and better adapt them to perform the functions required of them.

Further objects are to enable access to be had to the working parts for purposes of repair and the like and to enable the door to partially open before the checking device starts to operate, and to enable the hinge to be readily alined in position.

The invention consists of the improved construction hereinafter described in detail in the accompanying specification and drawings.

In the drawings, Figure 1 is a sectional perspective view of the improved hinge as seen fixed to the bottom of a door. Fig. 2 is a sectional plan of the hinge and the check case, showing the piston therein and the means for operating the same. Fig. 3 is a plan view of the hinge plunger looking from below. Fig. 4 is a perspective view of the combined cam base, check shaft support and crank support. Fig. 5 is a perspective view of the check operating pin. Fig. 6 is a sectional side elevation of the hinge plunger and spring attached thereto. Fig. 7 is a sectional detail through the check pin and support therefor.

In the drawings like characters of reference indicate corresponding parts in all the figures.

Referring to the drawings, A represents the floor plate, B the casing containing the check case C and carrying the spring pocket D.

E represents the supporting or connecting member, F the hinge pin and G the check pin. The member E relatively supports the check pin and connects the same with the floor plate.

The hinge which supports the door is suitably secured to the floor plate A and the

latter is secured to the floor by suitable means such as the wood screws 10. The supporting member E which serves as a combined cam base, check shaft and crank support is U-shaped in form and constructed with parallel top and bottom plates 11 and 12 connected by a plate 13 which is curved in cross section.

The alinement of the supporting member E on the plate A is controlled by suitable means, such as screws 14 and 15 provided in the plate E and which extend into a recess 16 in said plate and are there adapted to abut the opposite sides of an upstanding projection 17 on the floor plate. As the supporting member is pivotally mounted on the hinge pin it will be seen that its alinement may be readily adjusted by tightening one of the screws 14 or 15 and loosening the other.

The bottom plate 11 of the supporting member serves as a cam base or means by which the spring return mechanism H is caused to exert a pressure tending to return the door to its normal position. This spring device H includes a plunger 20 having a bifurcated end 21 which embraces the hinge pin, and is formed with a recess 22 in one end in which a pin 23 extends, such pin being supported from the casing B held in position by means of nuts 24 and 25 mounted on the screw threaded portion of the pin and embracing opposite sides of the casing E. A spiral compression spring 26 extends around the plunger H and abuts the nut 25 at one end, said nut being formed with an annular recess 27 to receive the spring.

The cam base or plate 11 is provided with a pair of cam rollers 30 and 31 carried on suitable pins embedded in the plate. These cam rollers are adapted to engage the head 32 provided on the plunger H, whereby when the door is swung open the head of the plunger engaging the cam roller will cause the plunger to be moved inwardly on the pin 23 to compress the spring 26, and the reaction of the plunger against the roller will tend to return the door to its normal position.

The checking device is included within the check case C conveniently formed integral with the casing and includes a cylinder 40, piston 41, connecting rod 42 which is articulated to the piston and connected at the opposite ends to the check pin G. This check pin extends through a perforation 44

in the supporting member, and is seated on its under side in the partition 46 between the check case and spring pocket. The check pin G is formed on its lower end with a crank pin 47 offset from the center of the pin. The check pin is allowed a limited amount of rotation with respect to the supporting member E and this is accomplished by forming the slot 45 of the shape shown in Fig. 7 and by cutting recesses 48 in the side of the check pin. It will be seen that the slot 45 is somewhat in the form of the numeral 3 and is provided with an aperture 49 at one end through which the pin may be introduced. In this way the check pin may turn a certain distance in either direction before it is stopped by the walls of the slot 45 and thus the check will not be caused to operate until the door has opened a certain amount.

The check case is filled with oil and a by-pass 50 is formed from one side of the piston to the other, being located in the wall of the casing and controlled by a valve in the form of a screw 51 extending through one side of the check case and abutting a valve seat 52 formed on the opposite side of the check case and through which the by-pass passageway opens. To give additional support to the check pin and to the supporting member E a flange 60 is formed on top of the casing extending parallel with the surface thereof and adapted to fit over the plate 12. The entire casing B is located in a suitable recess in the door L. The check case will contain oil or suitable liquid to retard the movement of the piston therein after the usual manner.

In the operation of the device, as the door is swung open the casing B revolves with the door relatively to the floor plate A and supporting member E in a horizontal plane, the oil passing from one side to the other of the piston 41 through the by-pass, and also if necessary through the perforation 62 provided in the piston. At the same time the spring device H is compressed as already explained, and upon being released this will operate to automatically close the door.

50. What I claim as my invention is:

1. A door check and closer comprising a casing mounted on the door, a check and spring return mechanism carried by the casing, a floor plate, a check pin supported from the floor plate, and operatively connected to the check, means extending from the floor plate to the spring return mechanism whereby the latter is operated.

2. A door check and closer comprising a casing mounted on the door, a check and spring return mechanism carried by the casing, a floor plate, means on the floor plate for operating the check and spring return mechanism, said means comprising a supporting member having a check pin at its

upper end and means connecting with the spring return mechanism at its lower end.

3. In a door check and closer, a casing adapted to be secured to the door, a flange formed on the top of said casing and extending parallel thereto and forming a pocket, alined openings in the flange and the top of said casing, a check within said casing, a check pin operatively connected to said check and extending through said alined openings, a floor plate, a hinge pin on said floor plate adapted to pivotally engage said casing, a supporting member mounted on said floor plate and extending upwardly therefrom, a plate extending at right angles therefrom adapted to enter the pocket between said flange and top of the casing and engage said check pin as and for the purpose specified.

4. A door check and closer comprising a casing secured to the door, a check carried thereby, a spring plunger mounted on said casing, a floor plate having a hinge pin engaging said casing, a supporting member connected to the floor plate and extending to the top of the casing, a check pin connected to the supporting member extending downwardly into the casing and connected to said check and means carried by the supporting member for operating said spring plunger.

5. A door check and closer comprising a floor plate having a hinge pin secured thereto, a supporting member comprising a bottom member mounted on said floor plate, a vertical member, and a top member extending from the said vertical member and substantially parallel to the bottom member, a casing, a check therein consisting of a cylinder, a piston operating in the said cylinder, said casing being pivotally mounted on said hinge pin and adapted to rotate in a horizontal plane.

6. In a door check and closer, a casing secured to the door, a check and a spring return device carried thereby, a floor plate, a hinge pin on the floor plate adapted to engage with said casing, a supporting member mounted on the floor plate and extending upwardly therefrom over the top of the casing, a check pin carried thereby, means operatively connecting said check pin to the check, means carried by said supporting member for operating said spring return device, and a flange on the top of the casing extending over the supporting member adapted for attachment to the door.

7. In a door check and closer, a casing, a check device therein, a spring return device carried thereby, a hinge pin, a floor plate upon which said pin is mounted, a supporting member secured to said floor plate and operatively connected to the check device and the spring return device, and means whereby the door may open a determined

amount before the check device starts to operate.

8. In a door check and closer, a casing, a check device and a spring return device carried thereby, a floor plate a hinge pin secured thereto, a supporting member secured to said floor plate and operatively connected to the check device and the spring return device, and means whereby the door may open a determined amount before the check device starts to operate, said means including a check pin independent of said hinge pin mounted in the supporting member and free to turn in a limited amount with respect thereto.

9. In a door check and closer, a casing, a check device therein, a spring return device carried thereby, a hinge pin, a floor plate

upon which said hinge pin is mounted, a supporting member secured to said floor plate and operatively connected to the check device and the spring return device, and means whereby the door may open a determined amount before the check device starts to operate, said means including a check pin independent of said hinge pin mounted in the supporting member and free to turn a limited amount with respect thereto, said check pin having a crank formed thereon to which the check is connected.

In witness whereof I have hereunto set my hand in the presence of two witnesses.

CHARLES EDWARD SANTO.
